UNITED STATES PATENT OFFICE.

JOHN C. CROMWELL, OF CLEVELAND, OHIO.

FORGING APPARATUS.

1,314,636.

Specification of Letters Patent.

Patented Sept. 2, 1919.

Application filed July 28, 1917. Serial No. 183,289.

To all whom it may concern:

Be it known that I, JOHN C. CROMWELL, a citizen of the United States, residing at Cleveland, in the county of Cuyahoga and State of Ohio, have invented a new and useful Improvement in Forging Apparatus, of which the following is a full, clear, and exact description, reference being had to the accompanying drawings, forming part of this specification, in which—

Figure 1 is a view partly in side elevation and partly in longitudinal vertical section of apparatus embodying my invention;

Fig. 2 is a view of the same partly in end elevation and partly in transverse vertical section;

Fig. 3 is a section on the line III—III of Fig. 1;

Fig. 4 is a detail sectional view showing a portion of the table roll gearing;

Fig. 5 is a longitudinal vertical section of one of the tables on a larger scale;

Fig. 6 is an end view of the anvil and its outboard bearings;

Fig. 7 is a side view partly in section of one of the outboard bearings removed;

Fig. 8 is a plan view of a portion of the apparatus showing the actuating mechanism; and

Fig. 9 is an end view of the mechanism shown in Fig. 8.

My invention has relation to forging apparatus, and more particularly to table mechanism therefor. In modern steel practice, there has been and is an increasing demand for heavy forging apparatus capable of efficiently handling heavy work. For instance, modern practice has demonstrated that to obtain the best quality of steel, it is desirable to break down the ingots by means of a hammer, instead of by a bloom-
ing mill, the action of the latter being injurious to the quality of the steel. Existing forging apparatus is incapable of properly handling this class of work. Its deficiency is largely due to the fact that the table and anvil mechanisms heretofore employed have not been capable of properly supporting and handling ingots and other large pieces. The tables which have been provided are not of a character to withstand the severe pounding action which they receive from the movements of the piece being forged under the action of the hammer, and soon crush or break.

The object of my invention is to provide a table mechanism of improved character which, combined with novel means for supporting the work piece, is capable of efficient and economical handling of heavy work and which will not be injured in operation.

The nature of my invention will be best understood by reference to the accompanying drawings, in which I have shown the preferred embodiment thereof, and which will now be described, it being premised, however, that various changes may be made in the details of construction, arrangement and combination of the several parts, without departing from the spirit and scope of my invention as defined in the appended claims.

In these drawings, the numeral 2 designates the frame of a power hammer, 75 3 the supporting legs or columns therefor, and 4 the hammer proper. 5 designates the anvil which may be, in general, of any usual or suitable construction. This anvil is shown as set in an anvil pit 6, upon a 80 concrete base 7, having extension 8, which form the supports for the hammer and also for the table bases, as shown in Figs. 1 and 2.

The numeral 9 designates the main tables, 85 one at each side of the anvil 5. Each of these tables consists of a suitable supporting frame in which are journaled a plurality of transversely extending roller members 10. In accordance with my invention, 90 these roller members, instead of being circular in cross section, have a cross section such that different portions of their peripheries are at different distances from the axes of rotation of the rollers. In the 95 particular form of my invention illustrated in the drawings, these roller members are of triangular cross section, but various other non-circular cross sectional forms may be employed. These rollers may be driven by 100 any usual or suitable gearing, such as the worm gearing 11, indicated in Figs. 3 and 4.

The normal position of the roller members when idle is such that one of the flat faces of each of them is in a substantially 105 horizontal plane, which is below the plane of the upper surface of the anvil block 5^a. The work piece (indicated at X in Figs. 1 and 2) is at this time supported entirely 110 free of these roller members and of the table frame by means of the anvil block 5^a, and of outboard bearings 12, one at

each side of the anvil block. Preferably, these bearings are detachably but securely mounted on the upper portion of the anvil base 5, which has the anvil block 5^a provided with the dovetailed portion 5^b (see Fig. 2). For this purpose, they may be provided with the grooved projections 12^a (see Fig. 7) which may be engaged in correspondingly shaped grooves in the upper portion 10 of the anvil base and firmly secured therein by bolts 13 and keys 14 (see Fig. 6) or in any other suitable manner. The upper faces of these outboard bearings extend above the plane of the upper surfaces of the roller members, so that they, together with the anvil, take the weight and blows of the work piece and entirely relieve the roller members and table frames thereof.

The numeral 15 designates lifters and manipulators for the work piece, each table being provided with a plurality of such lifters and manipulators. In the construction illustrated, I have shown each table as having two series of them arranged in two parallel lines, as best shown in Fig. 8. These manipulators are mounted in a carriage or carrier 16, as best shown in Fig. 5. This carrier or carriage is, in turn, mounted for movement transversely of the table and also 25 for vertical movement to raise and lower the manipulators in the spaces between the roller members. The mounting for transverse movement is effected by means of the shoes 17 (see Fig. 5) which have a sliding engagement with the rails or guides 18, and which loosely embrace the two manipulators at each end of the table. The carriage or carrier is mounted for vertical movement on the transverse rods or shafts 19 (on which it 30 also slides transversely) extending below the table frame, the carriage or carrier having the sleeve portions 20, which slidably engage these shafts. The transverse movement, which is for shifting the work piece 35 laterally, may be effected in any suitable manner. In the drawing, I have shown, for instance, (see Fig. 8) an electric motor 21, which is connected by gears 22, with a crank shaft 23, whose cranks are connected by pitmen 24 with said carriage or carrier. The vertical movement of the carrier and its manipulators may also be effected by any suitable means. In the arrangement shown in the drawings, I provide two bell cranks 25 and 26. The bell crank 25 is of three-armed form, one of the arms being connected to the said carrier, the second arm being connected to an actuating rod 27, and the third arm being counterweighted as indicated at 28 40 (see Fig. 5). This bell crank is pivoted to the table frame at 29. The bell crank 26 is pivoted to the table frame at 30, one of its arms being connected to the connecting rod 27, and the other arm to the carrier 16. The 45 connecting rod is actuated by the pitman 31,

connected thereto and to the crank pin 33, actuated by gear connections with an electric motor 34 (see Figs. 8 and 9).

The operation of this manipulator will be readily understood. It can be raised and lowered by the operation of the electric motor 34, and can be shifted from side to side by the operation of the motor 21, thereby giving complete control of the work piece.

The numeral 35 (Figs. 1 and 3) designates fixed guides on the table, and 36 designates auxiliary tables located beyond and forming the approach to or delivery from the main tables 9.

In accordance with my invention, I also 80 preferably provide movable guides, and while these may be mounted upon the table, I prefer to mount them upon the hammer. In the construction which I have illustrated, these movable guides are in the form of vertical rollers 37 (see Figs. 1 and 2). I have shown four of these rollers, two at each side of the anvil block, making two rollers at each side of the work piece. These rollers depend from and are journaled to the adjustable slide blocks or carriages 38, which are mounted for movement to and from the work piece on suitable guides 39. They can be adjusted by any suitable connections, such as the right and left threaded screw rods 40, 90 each of which is geared to an electric motor 41, mounted on the frame 2 of the hammer.

The advantages of my invention will be apparent to those skilled in this art, since it provides table mechanism for power hammers or forges capable of handling and manipulating extremely heavy work without injury to the tables or manipulator mechanisms. The provision of the outboard supports adjacent to the anvil block and extending above the roll members causes the entire weight and blows of the work piece to be received by the anvil, thus relieving the tables and their mechanisms. This constitutes a very important feature of my invention, as will readily be appreciated.

The peculiar form of the table rolls adapts them for use in connection with the outboard supports of this character, while at the same time providing rolls which are capable when 115 actuated of feeding the work piece as may be desired. The manipulator mechanisms are of simple and effective character and together with the movable guides give the operator complete control of the work piece. 120 Any suitable manipulator mechanism, however, may be used in connection with the main features of my invention.

I do not claim herein, *per se*, the hammer having guiding devices, as this forms the 125 subject matter of a separate application, serial No. 183,290; filed July 28, 1917.

I claim:

1. In a forging apparatus, the combination of an anvil, a feed table adjacent to said 130

anvil, said table having rotatable feeding members whose cross sectional shape is such that different portions of their peripheries are at different distances from their axes of 5 rotation, a rigid outboard work-support or bearing located at one side of the anvil and supported independently of the table, said work-support or bearing having its supporting surface at a higher level than the level 10 of the upper surface of the table feed members when the latter are in their lowest positions, substantially as described.

2. In forging apparatus, the combination with an anvil and work table adjacent thereto, of a rigid work support or bearing at 15 one side of the anvil, said support or bearing being independent of the table, substantially as described.

3. In forging apparatus, the combination with an anvil, of a feed table adjacent thereto, and a rigid work support or bearing extending upwardly through the feed table at 20 one side of the anvil to a level above the normal surface of the feed table, said support or bearing being independent of the table, substantially as described.

4. In forging apparatus, the combination with an anvil and feed tables adjacent thereto, of means for supporting the work independently of said tables, the tables having work-feeding members which are normally 25 below the level of the supporting surfaces of said supports, substantially as described.

5. In forging apparatus, an anvil base, an anvil thereon, and a rigid work-bearing member or support carried on the anvil base at one side of the anvil block and at a distance therefrom and forming an outboard work support for the apparatus, substantially 30 as described.

6. In forging apparatus, an anvil base, an anvil block thereon, and a rigid work-supporting member rigidly but detachably se- 40

cured to said base at one side of the anvil, substantially as described.

7. In forging apparatus, the combination with an anvil, of a feed table adjacent thereto, said feed table having rotatable feeding members of a cross sectional shape such that different portions of their peripheries are at 50 different distances from their axes of rotation, and rigid work-supporting means extending upwardly between the feeding members adjacent to the anvil, substantially as described.

8. In forging apparatus, a feed table having a plurality of rotatable feeding members, a vertically movable carriage having a plurality of vertically extending rigid lifting and manipulating members extending 60 between the feeding members of the table, means for moving said carriage vertically, and means for shifting said carriage laterally of the table, substantially as described.

9. In forging apparatus, the combination with a feed table, of a carriage having a plurality of rigid vertically extending lifting and manipulating fingers, shafts upon which the carriage is mounted and upon which it is shiftable laterally, bell crank 70 members connected to said shaft, and means for actuating said members to raise and lower the carriage, substantially as described.

10. In forging apparatus, the combination with a feed table, of a carriage having a plurality of rigid manipulator fingers adapted to extend upwardly through the feed table, vertically movable rods or shafts upon which the carriage is supported, and 80 means for moving said carriage transversely of the table, substantially as described.

In testimony whereof, I have hereunto set my hand.

JOHN C. CROMWELL.
